Attorney, Agent, or Firm—Wallenstein & Wagner, Ltd

[21] Appl. No.: 29/089,843

CLAIM

[22] Filed: Jun. 24, 1998

The ornamental design for a “handle for a window fan,” as
shown and described.

[51] LOC (6) Cl. 23-04

DESCRIPTION

[52] U.S. Cl. D23/411; D8/317

FIG. 1 is a front perspective view of a handle for a window
fan showing my new design;[58] Field of Search D23/370, 411,
D23/381, 382, 332; D8/316, 317; 416/63,
244 R, 247 R

FIG. 2 is an enlarged top plan view of the handle;

FIG. 3 is an enlarged front view of the handle;

FIG. 4 is an enlarged rear view of the handle;

FIG. 5 is an enlarged bottom plan view of the handle;

FIG. 6 is an enlarged left view of the handle; and,

FIG. 7 is an enlarged right view of the handle.

The broken-line showing of environmental structure in
FIGS. 1-4, 6 and 7 are for illustrative purposes only and
form no part to the claimed design.
